EX

OR D 5,553

UNITED STATES PATENT OFFICE.

GEORGE F. MEACHAM, OF NEWTON, ASSIGNOR TO JAMES W. TUFTS, OF MEDFORD, MASSACHUSETTS.

DESIGN FOR SODA-FOUNTAINS.

Specification forming part of Design No. 5,553, dated February 20, 1872.

To all whom it may concern:

Be it known that I, GEORGE F. MEACHAM, of Newton, in the county of Middlesex and State of Massachusetts, have invented and produced a new and original Design for the Casing of a Soda-Water Apparatus, of which the following is a full, clear, and exact description, reference being had to the accompanying photograph making part of this specification.

The object of this design is to relieve the rectangular casing of a soda-water apparatus of its box-like appearance; and consists in beveling or inclining inward the upper portion of the ends of the casing so as to contract the size of its top.

In the photograph, A represents the body or main portion of the casing of a soda-water apparatus, the lower portion of which is of rectangular form. B is the top, which is provided with moldings and other ornaments. The form of this top may, however, be varied,

if desired. Each end of the portion A is beveled or inclined inward from a to b, so as to diminish the size of the top of the apparatus, and thus relieve it of the box-like appearance which it would otherwise present, the design thus produced being unique and ornamental. At each corner of the casing is a pillar or standard, C, for a gas-burner. These pillars may, however, be dispensed with, if desired.

Claim.

What I claim as my invention, and desire to secure by Letters Patent, is—

The design for the casing of a soda-water apparatus herein shown and described.

Witness my hand this 12th day of January, A. D. 1872.

GEO. F. MEACHAM.

In presence of—

P. E. TESCHEMACHER,
G. A. MEACHAM.
